WELT SHOE AND METHOD OF MAKING
SAMEHarry L. Sutcliffe, Brooklyn, N. Y., assignor to
The Del-Mac Shoe Process Corporation, New
York, N. Y.

Application April 30, 1936, Serial No. 77,102

8 Claims. (Cl. 12—142)

This invention relates to welted shoe constructions and to the methods by which they are made.

The general advantages of welt shoes, including their superior shape holding, fitting, and rugged wearing qualities, are too well known to require more than brief mention. However, the same structural characteristics which obtain these advantages have also been responsible for their greater weight and relative stiffness compared to other types of shoes.

In making welt shoes it has for many years been the standard practice to attach the margins of the upper parts and the welt by inseam stitching to the root of an integral rib extending from the margin of the insole, the rib being formed by a pair of channel leaves or lips erected from the surface of the insole and usually supplemented by the marginal portion of a fabric insole reinforcement. The resulting structure is therefore characterized by a wide ridge comprising five or six plies of material which project from the inseam on the flesh side of the insole and form a stiff wall between the sole members, the plies comprising the inner margins of the welt and of the upper and its lining, the channel leaves or lips, and the outer margin of the fabric reinforcement. I have found that this ridge is the principal factor mitigating against flexibility in welted constructions.

It is a principal object of my invention, therefore, to provide an improved welt shoe having fewer plies of material projecting perpendicularly from the inseam, and an improved shoemaking method for obtaining this structural improvement.

To compensate for the marginal ridge between the sole members, it has long been customary to assemble filler material between them at the forepart of the shoe inwardly of the inseam. Such material contributes to deprive the shoe of flexibility, adds to the weight of the shoe bottom, and is a frequent source of discomfort to the wearer if the material is injudiciously selected or improperly assembled, or if for other reasons it becomes wrinkled, unevenly compacted, or otherwise displaced.

Another principal object of my invention, therefore, is to provide an improved welt shoe in which all parts projecting at the inseam will terminate flush with the lower surface of the insole, thereby providing a smooth and solid bottom, devoid of filler, creases, gutters or ridges.

A further object is to provide an improved shoe in which the foregoing objects are attained and in which the inseam rib is transversely slashed

between the stitches to further increase the flexibility of the shoe. Other and further objects will appear from the following specification.

Referring to the drawings which form a part of this specification:

Figure 1 is a plan view of a lip channeled insole prepared in accordance with my invention.

Figure 2 is a longitudinal edge elevation of the insole prepared as shown in Figure 1.

Figure 3 is a sectional view of the insole margin taken on line 3—3 of Figure 1.

Figure 4 is a plan view showing the insole, the welt and the upper parts assembled together on a last, the lip members and between substance of the insole being transversely slashed between 15 stitches of the inseam to render the forepart of the shoe more flexible.

Figure 5 is a sectional view taken on line 5—5 of Figure 4.

Figure 6 is a perspective view, partly in section, illustrating the manner in which the slash cuts 20 may be formed progressively as the inseam is sewn.

Figure 7 is a sectional view showing the relationship of the assembled parts after the inseam 25 trimming operation has been performed.

Figure 8 is a cross sectional view of the lasted shoe with the outsole attached, taken thru slash cuts at or about line 8—8 of Figure 4.

Figure 9 is a perspective view of the finished 30 shoe transversely divided at the forepart to show the inseam construction in cross section, a part of the upper being broken away at the toe portion to disclose the relation of the box toe reinforcement to the other parts of the shoe.

In carrying out my invention I provide a rounded insole 15 which is lipped and channeled forwardly of the heel entirely about the shank and forepart margins, providing an inner channel leaf 16 and an outer marginal lip 17. The channel is 35 opened in the usual manner and the lip 17 is rolled back and adhesively secured over the between substance 19 located between the roots of the members 16 and 17, thereby forming a marginal shoulder 20 having height approximately 40 double the thickness of the lip 17 and exposing a marginal feather 21. I may then adhesively secure a layer of fabric 23, such as canvas or duck, to the channeled surface of the insole, the 45 margins of the fabric extending to face and reinforce the leaf 16 and overextending the edges of the leaf substantially as shown.

After the lip is turned back, I prefer to reduce the feather 21 about the toe portion 22 of the insole, as best illustrated in Figure 2, to compen- 50

sate for the greater thickness of the upper parts occasioned by the insertion of the usual box toe reenforcement 37. The reduced portion of the feather merges with the unreduced portions 5 thereof on a long slope 22' so that the varying thickness of the upper parts adjacent the skived rearward edge of the box toe reenforcement will be evenly accommodated.

Prepared as above described, the insole is 10 tacked channeled-side-up to the bottom of a last 38 and the upper parts are pulled over the last onto the feather 21 and against the shoulder 20 where they are secured either by temporary lasting tacks or by staples as in the usual manner 15 of lasting to shouldered sole members. The upper parts, together with a welt 40, are then secured to the insole by inseam stitching 42 which extends thru the welt, the upper parts, the between substance and the fabric into the channel 20 18, the upper parts including the lining 36 and the box toe reenforcement 37.

The lip 17 turned in and secured against the insole increases the marginal thickness of the insole and would ordinarily increase the stiffness 25 of the shoe. Therefore, as best shown in Figures 4 and 6, I prefer to make a plurality of transverse slash cuts 45-45 through the inner portion of the seam comprising the upstanding edge margin of the fabric insole reenforcement, 30 the channel leaf, the between substance, and the lip. These slash cuts preferably extend to a depth corresponding to the bottom of the inseam thread and may also extend thru the upper parts, if desired. However, I prefer not to cut thru the 35 upper parts at the inseam although the sweep of the slashing blade may pass thru the untrimmed surplus portions of the upper parts as shown.

The cuts 45 are formed progressively as the inseam is sewn in the manner taught in my co- 40 filed application Serial No. 77,103, a cut being made in advance of each stitch. The procedure followed is best illustrated in Figure 6 in which a hand stitched seam is shown in the course of its formation. After the completion of a stitch, an 45 awl hole is formed for the reception of the next stitch; a transverse slash cut is then made intermediate the stitch and the awl hole, whereupon the next stitch is formed, and so on entirely about the inseam or such parts thereof as may be desired, any temporary lasting tacks being removed. I have illustrated the slash cuts as formed only 50 at the margins of the ball portion of the shoe, leaving the seam comparatively stiff throughout the shank and toe portions where great flexibility 55 is neither necessary nor desirable.

After the inseam has been sewn and before the surplus material projecting therefrom has been trimmed away, the channel leaf 18, together with the facing marginal portion of the reenforcement 60 23, is cemented down over the stitching to close the channel 18, thereby protecting the inside stitching and permanently holding the inseam in position to enhance the shape holding qualities of the shoe. Because the double thickness of fabric 65 now lies in the channel, the leaf is somewhat foreshortened and its edge will not quite extend to fill the portion of the channel from which it was removed. However, the edge margin of the fabric 70 23 overextending the edge of the leaf will merge into the shallow inner portion of the channel, smoothly filling it as shown in dotted lines in Figure 5.

The remaining material projecting from the insole at the inseam is then trimmed away on a 75 line coincident with the surface of the welt and

the reenforced surface of the insole, substantially parallel with the bottom of the last but safely above the inseam stitching 42, a portion of the lip 17 being removed by the trimming cutter so that a smooth and flush surface is obtained, as shown in Figure 7. The trimming operation may be performed by hand or by means of a standard inseam trimming machine. However, I prefer to employ an inseam trimming machine equipped as described in the co-filed application of Edward 10 Quinn, Serial No. 77,105.

It will be observed that by laying down the leaf 16 and the margin of the fabric 23, the number of the projecting plies of material is substantially reduced in comparison with welt shoes as usually 15 constructed. Also, that the trimmed edges of the welt and upper parts do not extend above the central surface area of the insole, so that there are no surface inequalities to be compensated for by filler material. Regarded in one aspect, the 20 seam may be compared to the seam in a shoulder channeled turned shoe wherein the channel leaf is closed down over the stitching, although in such shoes the leaf cannot be adhesively secured in position because of the wet condition in which 25 a turn sole is lasted.

The shoe is completed by securing an outsole 30 50 to the welt, as by the outer line of stitching 51, attaching a heel 52, assembling a sock lining 53, and performing such other usual and necessary 55 operations.

In the finished shoe it will be found that the outsole lies flush under the channel leaf and inseam as well as under the welt and the reenforced insole, no gutters, ridges, or creases existing between the sole members and no filler being required or desirable, although a thin layer of material may be interposed between the sole members to reduce friction between them or to waterproof the shoe bottom, any such layer preferably overextending the channel leaf. 40

It will also be noted that the welt and the upper parts are all secured to the insole above a line parallel with the last and coincident with the lower face of the insole reenforcement, even 45 about the toe portion where the thickness of the upper parts is increased by the box toe reenforcement 37, so that the inner surface of the shoe bottom is evenly supported over its entire area. Devoid of filler material and having a comparatively light inseam construction, the shoe is inherently light and flexible, its flexible qualities 50 being enhanced by the transverse slash cuts extending thru the assembled parts at the ball portion. 55

I desire to have it understood that where the insole is not required to be reenforced, the fabric 23 may be entirely dispensed with, in which case the channel leaf will not be foreshortened materially and will fill the channel completely. 60

If desired, the flexibility and wearing qualities of the shoe may be further enhanced by employing an insole having a skeletonized forepart and a complementary outsole of the type taught in U. S. Patent No. 2,012,914 granted to Fred Mac- 65 carone, or as taught in his application Serial No. 57,715 filed January 6, 1936, such modifications being within the scope of the appended claims.

Wherever the "upper" is referred to in the appended claims it is intended to include any lining, plumping or reinforcing material, and wherever the "insole" is recited in the claims it is intended to include any insole reinforcing such as is commonly employed in making welt shoes.

I claim:

1. A shoe comprising an insole having a marginal lip, a stitch channel extending parallel with the lip inwardly thereof, and an integral leaf for said channel, said lip being turned in against the lower surface of the insole and adhesively secured thereto to form a firm marginal shoulder, an upper, a welt, stitching securing the upper and welt against said shoulder and extending into said channel, adhesive securing said leaf in the channel to protect the stitching and to brace the seam secured thereby, the inturned portion of said lip being skived and lying flush with said leaf and with said welt and forming an integral marginal filler, and an outsole secured to said welt.

2. A shoe comprising an insole having a marginal lip, said lip being turned in against the lower surface of the insole and adhesively secured thereto to form a firm marginal shoulder, an upper and a welt secured against said shoulder, and an outsole secured to the welt, the inturned portion of said lip of the insole being skived and lying flush with the central portion of the lower surface of the insole and with said welt and forming an integral marginal filler.

3. A shoe comprising an insole having a marginal lip, a stitch channel extending parallel with the lip inwardly thereof, and an integral leaf for said channel, said lip being turned in against the lower surface of the insole and adhesively secured thereto to form a firm marginal shoulder, an upper, a welt, stitches securing the upper and welt against said shoulder and extending into said channel, adhesive securing said leaf in the channel to protect the stitching and to brace the seam secured thereby, the inturned portion of said lip being skived and lying flush with said leaf and with said welt and forming an integral marginal filler, said insole having a plurality of slash cuts formed in the lower surface thereof extending outwardly from the bottom of said channel and thru the lip between stitches, and an outsole secured to said welt.

4. A shoe comprising an insole having a marginal lip, said lip being turned in against the lower surface of the insole and adhesively secured thereto to form a firm marginal shoulder having height greater than the thickness of the lip, an upper and a welt secured against said shoulder, said insole having a plurality of slash cuts formed therein extending thru the shouldered portion thereof and thru said lip, the inturned portion of said lip being skived and lying flush with the central portion of the lower surface of the insole and with said welt and forming an integral marginal filler, and an outsole secured to said welt.

5. In methods of making welt shoes, that improvement which comprises providing an insole having a marginal lip, a stitch channel extending parallel with the lip inwardly thereof, and an integral leaf for said channel, the lip being turned inwardly and adhesively secured to the insole to form a firm marginal shoulder having depth greater than the thickness of the lip, stitching the margins of an upper and a welt to

the insole against said shoulder in inseamed relation, said stitching being extended into the channel, adhesively securing said leaf in the channel to protect the stitching and to brace the inseam secured thereby, trimming in a plane coincident with the surfaces of the welt and said leaf to remove part of the inturned portion of said lip and to cut off any surplus of said upper and welt, and securing an outsole to the welt.

6. In methods of making welt shoes, that improvement which comprises providing an insole having an integral marginal lip, the lip being turned inwardly and adhesively secured to the insole to form a firm marginal shoulder having depth greater than the thickness of the lip, securing the margins of an upper and a welt to the insole against said shoulder, trimming in a plane coincident with the surface of the welt and said leaf to remove part of the inturned portion of said lip and to cut off any surplus of said upper and welt, and securing an outsole to the welt.

7. In methods of making welt shoes, that improvement which comprises providing an insole having an integral marginal lip turned inwardly and adhesively secured to the insole and forming a marginal shoulder having depth greater than the thickness of the lip, securing the margins of an upper and a welt to the insole against said shoulder, cutting a plurality of incisions in the margin of the insole said incisions being extended thru said lip and to the depth of the shoulder, trimming in a plane coincident with the surface of the welt and said leaf to remove part of the inturned portion of said lip and to cut off any surplus of said upper and welt, and securing an outsole to the welt.

8. In methods of making welt shoes, that improvement which comprises providing an insole having a marginal lip, a stitch channel extending parallel with the lip inwardly thereof, and an integral leaf for said channel, the lip being turned inwardly and adhesively secured to the insole and forming a marginal shoulder and a marginal feather, said feather being reduced about the toe portion of the insole and merging with the unreduced feather on a long angle corresponding to the skived edges of a box toe reinforcement, securing the margins of an upper together with the box toe reinforcement and a welt to the insole against said shoulder in inseamed relation, the stitches of the sewing thread being extended into the channel, and cutting a plurality of slash cuts in the margin of the insole between stitches of the inseam thread, said slash cuts extending outwardly of the channel thru said lip to a depth corresponding with the bottom of the channel, adhesively securing said leaf in the channel, trimming in a plane coincident with the surface of the welt and said leaf to remove part of the inturned portion of said lip and to cut off any surplus of said upper and welt, and securing an outsole to the welt.
